US00D997504S

(12) United States Design Patent (10) Patent No.: US D997,504 S
(45) Date of Patent:  Sep. 5, 2023

(54) SHOE

(71) Applicant: Valentino S.p.A., Milan (IT)

(72) Inventor: Pierpaolo Piccioli, Milan (IT)

(73) Assignee: VALENTINO S.p.A., Milan (IT)

() Term: 15 Years

(21) Appl. No.: 35/514,852

(22) Filed: Jul. 18, 2022

(80) Hague Agreement Data

Int. Filing Date: Jul. 18, 2022

Int. Reg. No.: DM/222419

Int. Reg. Date: Jul. 18, 2022

Int. Reg. Pub. Date: Aug. 5, 2022

Primary Examiner — Jonathan J Han

(74) Attorney, Agent, or Firm — Ferguson Case Orr Paterson

(57) CLAIM

The ornamental design for a shoe, as shown and described.

DESCRIPTION

1. Shoe
- 1.1 : Perspective
- 1.2 : Front
- 1.3 : Back
- 1.4 : Left
- 1.5 : Right
- 1.6 : Top
- 1.7 : Bottom

The drawings only show the design on the left shoe, the right shoe is omitted as it is symmetrical to the left shoe.

1 Claim, 7 Drawing Sheets
